FOUNTAIN PEN CAP HAVING AN INK
CONTAINER THEREIN

Mendel Fried, Brooklyn, N. Y.

Application April 26, 1952, Serial No. 284,513

13 Claims. (Cl. 120—7.5)

1

The present invention relates to a pen cap structure and more particularly to a pen cap structure having a container in which ink may be located.

One of the objects of the present invention is to provide a pen cap structure with a means for holding ink.

Another object of the present invention is to provide, in a pen cap structure, an ink holder which is adapted to form a permanent part of the pen without substantially altering the outward appearance thereof.

An additional object of the present invention is to provide, in a pen cap structure, an ink container which can automatically assume an upwardly directed position.

Still another object of the present invention is to provide a convenient source of ink for a fountain pen and a means for conveniently filling the pen from the source of ink.

Yet another object of the present invention is to provide a means for stably supporting an ink container forming part of a pen cap structure.

It is also an object of the present invention to provide a structure capable of accomplishing all of the above objects while at the same time being made of relatively few, simple, inexpensive parts.

With the above objects in view the present invention mainly consists of a pen cap structure adapted to be removably connected to a pen for covering the point thereof. This pen cap structure includes an elongated tube having an open end portion in which a pen point is adapted to be located and having another end opposite the open end portion thereof. An elongated container is movably connected to this other end of the tube for movement between one position where the container forms an extension of said tube and another position where the container extends at an angle from said tube. It is preferred to provide a resilient means for urging the container into this other position and a means for stably supporting the container in an upwardly extending direction in this other position thereof. Also, a releasable holding means is associated with the tube and the container for releasably holding the latter in said one position where the container forms an extension of said tube.

The novel features which are considered as characteristic for the invention are set forth in particular in the appended claims. The invention itself, however, both as to its construction and its method of operation, together with additional objects and advantages thereof, will be

2

best understood from the following description of specific embodiments when read in connection with the accompanying drawings, in which:

Fig. 1 is a side sectional view of a pen cap structure constructed in accordance with the present invention and shown associated with a pen;

Fig. 2 shows the pen cap structure of Fig. 1 in a different position thereof;

Fig. 3 shows another embodiment of the pen cap structure of Figs. 1 and 2 in the position corresponding to that of Fig. 2;

Fig. 4 is a partly sectional view illustrating yet another embodiment of the present invention;

Fig. 5 shows the embodiment of Fig. 4 in a position corresponding to that of Fig. 2;

Fig. 6 is a view of the structure of Fig. 5 as seen from the left-hand side thereof; and

Fig. 7 is a fragmentary, partly sectional view of a pen constructed in accordance with the invention and illustrated in use with other structure of the invention.

Referring now to the drawings, there is shown in Fig. 1 a pen 10 which in the particular embodiment illustrated is a fountain pen. An open end portion of a tube 11, which may be cylindrical and which is provided with inner threads, threadedly engages the threads of the pen 10. This tube 11 has tightly located therein a member 12 which is also cylindrical and over which is stretched an end of a rubber tube 13, this end of the rubber tube 13 being tightly clamped between the members 11 and 12 so as to be fixed to the tube 11. The rubber tube 13 is fixed, as by glueing or the like, to the bottom closed end of a tubular container 14 adapted to have ink located therein, this container 14 preferably being made of a transparent material such as glass or plastic and having a cover 15 threadedly mounted thereon over the open end thereof distant from tube 11. The tube 13 is stretched to a greater degree on its lower side, as viewed in Fig. 1, than on its upper side so that with the parts in the position shown in Fig. 1 the rubber tube 13 will resiliently urge the container 14 in a counterclockwise direction about the left end of tube 11, as viewed in Fig. 1.

A holding means is provided to maintain the container 14 in the position shown in Fig. 1 where it forms an extension of the tube 11, the members 11 and 14 both being cylindrical and of substantially the same diameters. In the embodiment of Fig. 1 this holding means takes the form of an elongated tube 16 having a closed end 17 and slidably engaging the tube 11 which may

be provided with a slightly enlarged tapered portion $11a$ terminating in a shoulder 16 to limit the movement of tube 16 . The right-hand open end of tube 16 frictionally engages the tapered portion $11a$ of tube 11 so as to be maintained thereon by the force of friction and is removable from the tube 11 with a relatively slight pulling force. A spring clip 19 is attached to the tube 16 so that when the parts are in the position shown in Fig. 1 they closely resemble a conventional fountain pen.

The pen 10 is usable simply by being unthreaded from the tube 11 and may have its end 20 located within the tube 11 as in conventional fountain pens when the pen is being used. When the ink in the pen 10 is exhausted it is only necessary to remove the tube 16 from the tube 11 and container 14 . The rubber tube 13 will then automatically move the container 14 to the position shown in Fig. 2, and the spring clip 19 may be inserted into the tube 11 so that the tubes 16 and 11 form a stable support for holding the container 14 in a generally upward direction, as shown in Fig. 2. Then the cap 15 may be removed from the container 14 and the pen 10 conveniently filled. The parts may then be reassembled in the position shown in Fig. 1.

In order to prevent relative movement between the pen and the relatively small neck of container 14 , the pen 10 is provided adjacent the point thereof with a conical part 30 adapted to tightly engage the mouth of container 14 so that the container is firmly connected to the pen and will not move relative thereto during filling of the pen.

As is illustrated in the dotted lines in Fig. 1, the conical part 30 of the pen may be formed with a groove or cut away portion 31 so that air may pass through the neck of container 14 during filling or emptying of the pen. This feature is of particular significance when the container 14 is being filled. However, the pen 10 itself may be used to fill container 14 by emptying ink from the pen into the container, and when this is being done the cut away portion or groove 31 permits air to move out of the container 14 as it is being filled with ink. The small size of the outlet of container 14 produces a capillary action which prevents ink from spilling from the container.

A variation of the above embodiment is illustrated in Fig. 3 where all of the parts are the same as those described above except that the resilient tube 13 is replaced by a leaf spring 21 fixed to the bottom end of container $14'$ and the end of tube $11'$ opposite the threaded end thereof. The parts are shown in Fig. 3 in the position corresponding to that of Fig. 2 and may be assembled in the position corresponding to that of Fig. 1.

In Fig. 4 there is shown a further embodiment of the invention where the tube $11''$, corresponding to the tubes $11'$ and 11 , is connected by a leaf spring $21'$ to the bottom end of a container $14''$ having the same construction as the containers described above. In the embodiment of Fig. 4 the leaf spring $21'$ is connected to and located in a recess of a side of the tube $11''$ so that it need not be bent to the same degree as the leaf spring 21 of Fig. 3. The leaf springs 21 and $21'$ may be connected to the containers and tubes associated therewith by any suitable means, such as glueing or the like.

In the embodiment of Fig. 4 instead of a holding means having the construction of tube 16 of

Fig. 1, there is provided an elongated member 22 fixed to the container $14'$ as by glueing, or the like, and extending beyond the bottom end thereof into a recess in the side of tube $11'$ opposite to the point about which container 14 turns under the influence of spring $21'$ when the parts are in the position shown in Fig. 4. As is shown in Fig. 4, the tube $11''$ is formed with an opening 23 through which a projection 24 mounted on the member 22 extends to releasably hold the parts in the position shown in Fig. 4. When projection 24 is moved out of the opening 23 the spring $21'$ will automatically move the container $14''$ to the position shown in Fig. 5. As is apparent from Fig. 6, the lower free end portion of member 22 is rectangular so that it stably holds the container $14''$ in an upwardly extending direction, even though the tube $11''$ is cylindrical, when the parts are mounted on a flat horizontal surface. It is obvious that a spring clip may be conveniently connected to any part of the structure shown in Fig. 4 to enable the same to be conveniently carried by the user.

The pen $10''$ shown in Fig. 4 is connected to member $11''$ in the same way as in the embodiment of Fig. 1. However, instead of a conical portion 30 as is the case with pen 10 , the pen $10''$ is provided with a cylindrical lip 32 adjacent the point thereof and this lip is adapted to be located about the neck of container $14''$ and is provided with internal threads 33 which engage the threads on container $14''$ when the pen $10''$ is being filled or is being emptied to fill container $14''$ so that in this way the container $14''$ is removably connected to the pen $10''$ so as to be substantially immovable with respect thereto when either the pen $10''$ or the container $14''$ is being filled.

It is also possible to substitute a hinge for the spring $21'$ so that element 22 will then simply serve as a supporting leg to hold the structure in the position shown in Figs. 5 and 6. Also, the recess 23 and projection 24 could be omitted and the apparatus of Figs. 4-6 could be inserted in the tube 16 , shown in Fig. 1.

Fig. 7 illustrates a preferred pen construction $31'$ adapted to be used with tubes 11 , $11'$ or $11''$ and with a container $30'$ of the same construction as the containers 14 , $14'$ or $14''$. The pen $31'$ has a curved, spherical part $32'$ adapted to rest against the mouth of container $30'$ and cover the same. A tubular extension $33'$ extends downwardly from spherical part $32'$ and carries pen point 34 . Extension $33'$ is of a slightly smaller diameter than the mouth of container $30'$. Extension $33'$ places point 34 near the bottom of the container not only to draw ink from the container when it is almost empty but also to enable the pen point and lower part of extension $33'$ to be completely submerged in ink so that no air will be drawn into the pen when it is being filled.

It will be understood that each of the elements described above, or two or more together, may also find a useful application in other types of pen cap structures differing from the types described above.

While the invention has been illustrated and described as embodied in pen cap structures having an ink container therein, it is not intended to be limited to the details shown, since various modifications and structural changes may be made without departing in any way from the spirit of the present invention.

Without further analysis, the foregoing will so

fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A pen cap structure adapted to be removably connected to a pen for covering the point thereof and comprising, in combination, an elongated tube having an open end portion in which a pen point is adapted to be located and having another end opposite said open end portion thereof; an elongated container having a bottom closed end located next to said other end of said tube; resilient means interconnecting said other end of said tube with said bottom end of said container for urging the latter into a first position where said container extends angularly from said tube; and releasable holding means associated with said tube and container for holding the latter against the action of said resilient means in a second position where said container forms an extension of said tube so that when said holding means is released said container will automatically move into said first position under the influence of said resilient means.

2. A pen cap structure as defined in claim 1 and wherein said releasable holding means is in the form of a second tube located about said container and first-mentioned tube and frictionally engaging the latter to hold said container against the action of said resilient means in said second position.

3. A pen cap structure as defined in claim 2 and wherein said second tube is provided with a spring clip for holding the pen on an edge portion of an article of clothing and adapted to be inserted into said open end portion of said first-mentioned tube to stably hold the latter in a position where said container extends upwardly from said first-mentioned tube in said first position thereof.

4. A pen cap structure as defined in claim 1 and wherein said resilient means is in the form of a leaf spring connected to said other end of said tube and said bottom end of said container.

5. A pen cap structure as defined in claim 1 and wherein said resilient means is in the form of a rubber tube fixedly connected to said other end of said first-mentioned tube and to said bottom end of said container.

6. A pen cap structure as defined in claim 1 and wherein said resilient means is in the form of a rubber tube fixedly connected to said other end of said first-mentioned tube and to said bottom end of said container, said rubber tube being unequally tensioned on opposite sides thereof to automatically urge said container into said first position.

7. A pen cap structure as defined in claim 1 and wherein said resilient means is in the form of a rubber tube fixedly connected to said bottom end of said container, and wherein a clamping member is inserted into said rubber tube to stretch the same and is pressed into said other end of said first-mentioned tube with said rubber tube located between said first-mentioned tube and said clamping member so as to be fixed to said first-mentioned tube.

8. A pen cap structure as defined in claim 2

and wherein said container, first-mentioned tube, and second tube are all substantially cylindrical and said container and first-mentioned tube are of substantially the same diameter.

5 9. A pen cap structure as defined in claim 1 and wherein said releasable holding means is in the form of an elongated member fixedly connected to said container and being releasably connected to said tube for releasably holding said container in said second position.

10 10. A pen cap structure as defined in claim 1 and wherein said tube is formed in a side portion thereof with an opening passing therethrough and said releasable holding means is in the form

15 of an elongated member fixedly connected to said container and having a projection thereon movable into and out of said opening in said tube for releasably holding said container in said second position thereof when said projection is located in said opening.

20 11. A pen cap structure adapted to be removably connected to a pen for covering the point thereof and comprising, in combination, an elongated substantially cylindrical tube having an open end portion in which a pen point is adapted

25 to be located and having another end opposite said open end portion thereof, said tube being formed with an opening in a side portion thereof; an elongated substantially cylindrical container of substantially the same diameter as said tube and having a closed bottom end located

30 next to said other end of said tube; resilient means interconnecting said other end of said tube with said bottom end of said container for

35 resiliently urging the latter from a first position where said container forms an extension of said tube about a point located substantially on the periphery of said other end of said tube on the side opposite said side portion thereof to a second position where said container extends angularly from said tube; and an elongated member fixedly connected to said container adjacent said bottom end thereof and having a substantially rectangular free end portion extending beyond said container and overlapping said side portion of said tube when said container is in said first position thereof, said elongated member having a projection located in said opening of said tube to releasably hold said container in said first position against the action of said resilient means, and said rectangular free end portion of said elongated member serving to stably hold said container in an upwardly extending direction when said tube is mounted on a horizontal surface and said container is in said second position thereof.

40 12. A pen cap structure adapted to be removably connected to a pen for covering the point thereof and comprising, in combination, an elongated tube having an open end portion in which a pen point is adapted to be located and having another end opposite said open end portion thereof; an elongated container having a closed bottom end located next to said other end

45 of said tube; connecting means interconnecting said other end of said tube with said bottom end of said container to mount the latter for turning movement from a first position, where said container forms an extension of said tube, about a point located on the periphery of said other end of said tube to a second position where said container extends angularly from said tube; and an elongated member fixedly connected to said container adjacent said bottom end thereof and having a substantially rectangular free end portion

55

60

65

70

75

tion extending beyond said container and overlapping a side portion of said tube located opposite said turning point when said container is in said first position thereof, so that, when said container is moved about said turning point to said second position, said rectangular free end portion of said elongated member serves to stably hold said container in an upwardly extending direction when said tube is located on a horizontal surface.

13. A pen cap structure adapted to be removably connected to a pen for covering the point thereof and comprising, in combination, an elongated, substantially cylindrical tube having an open end portion in which a pen point is adapted to be located and having another end opposite said open end portion thereof; an elongated, substantially cylindrical container of substantially the same diameter as said tube and having a closed bottom end located next to said other end of said tube; connecting means interconnecting said other end of said tube with said bottom end of said container to mount the latter for turning movement from a first position, where said container forms an extension of said tube, about a point located on the periphery of said other end of said tube to a second position where said container extends angularly from said tube; and an elongated member fixedly connected to said

5 container adjacent said bottom end thereof and having a substantially rectangular free end portion extending beyond said container and overlapping a side portion of said tube located opposite said turning point when said container is in said first position thereof, so that, when said container is moved about said turning point to said second position, said rectangular free end portion of said elongated member serves to stably hold said container in an upwardly extending direction when said tube is located on a horizontal surface.
